UNITED STATES PATENT OFFICE.

CHARLES K. McDERMOTT, OF CHARLESTON, WEST VIRGINIA.

RAIL FASTENING AND GAGE.

1,107,085.

Specification of Letters Patent. Patented Aug. 11, 1914.

Application filed December 9, 1913. Serial No. 805,593.

To all whom it may concern:

Be it known that I, CHARLES K. McDERMOTT, a citizen of the United States, residing at Charleston, in the county of Kanawha and State of West Virginia, have invented certain new and useful Improvements in Rail Fastenings and Gages, of which the following is a specification.

This invention relates to improvements in rail fastenings and gages.

The invention has for its object primarily to provide for suitably securing or fastening rails, especially of railways, in place and effectively against displacement.

A further object is to provide for suitably gaging or adjusting the rails in maintaining the gage as the sides of the balls of the rails as they wear away.

A still further object is to provide for carrying out the aforesaid ends in a simple, expeditious and effective manner.

The invention therefore consists of certain instrumentalities, together with structural features, substantially as hereinafter fully disclosed and defined by the appended claims.

In the accompanying drawings is illustrated the preferred embodiment of my invention, wherein it will be understood that various changes and modifications as to the detailed parts may be made without departing from the spirit of the invention, and in which drawings—

Figure 1 is a side elevation of my invention as applied for use in connection with a railway rail and accessory parts, the latter, together with the railway rail, being shown in section. Fig. 2 is a like view of the same parts, showing the same in locked position. Figs. 3 and 4 are disassembled perspective views of the slidable interacting or interlocking members or levers. Fig. 5 is a plan view of the tie-plate partly mutilated. Fig. 6 is a side view of the wedge or cam action member. Fig. 7 is a modification, in side view of the wedge or cam action member.

In carrying out my invention, I employ in connection with a tie-plate or bar 1 of a metallic, concrete or wooden tie, a screw-threaded or bolt-like wedge action member 2 and two interacting or interlocking members or levers 3 and 4, said latter members being adapted to be actuated by the member 2, as will presently more fully appear. The members 3 and 4 are plate-like in gen-

eral outline and have alining elongated slots or apertures 5 and 6, respectively, which receive the shank or body portion 7 of the wedge-action member 2 and so as to allow of a compound or vertical and horizontal or lateral movement of said members 3 and 4, as said wedge action member is actuated. The member 3 has a plane or horizontal portion 8 terminating at one end in an extension or tongue 9 and an inclined portion 10, terminating at one end in an extension or tongue 11. The member 4 is downwardly extended at its ends, as at 12, 13 respectively, one end extension 13 having an aperture 14 therein and a horizontal outwardly projecting tongue 15, the other end extension 12 having a tongue 16 struck up therefrom and inclined upwardly to conform to and bear upon the base or foot of the rail, as clearly shown, said struck-up tongue forms a slot 17 in the end-extension 12. The tongues 9 and 11 of the plate of member 3 are received by the openings or apertures 14 and 17 of the member 4, while the tongue 15 is inserted or passed downwardly through an opening 18 in the tie plate or bar 1 and is caused to take under the latter, the shoulders 20 resulting from the formation of the tongue 15 resting upon the tie-plate and thus limiting the downward insertion of that end of the member 4. The tongue 11 of the member 3 is inserted through an aperture 19 in the tie-plate 1 and takes under the latter. It will be noted that the inclined portion 10 of the member 3 engages the opposed inclination of the wedge-formation of the member 2, the other inclination of the latter member being engaged by a downwardly turned or inclined extension or projection 21 of the tie-plate 1, the action of which arrangement of parts, it will be seen has the effect, as the nut 22 upon the wedge action member 2 is suitably actuated to bring the members 3 and 4 forcibly together and accordingly cause the tongues 11 and 16 of said members to grip the rail base or foot and thus provide for firmly or effectively securing the rail in position. The extension or projection 21 of the base plate 1 is recessed or cut away, as at 23, for clearance of the bolt-like portion or body 7 of the cam action member 2, as the parts are brought to locked position. It is also observed that the tie-plate may be either plane or corrugated in its surface of contact with the wedge action member.

In the modification as suggested by Fig. 7, the wedge or cam action member 2 may be substituted by an incline-plane member 2^a, one face of the latter being perpendicular in 5 this instance, as seen, while the other face only is produced upon an incline; also this device may be applied to the common or well-known metallic type of tie, as is apparent. It is also noted that the device is 10 adapted to provide for maintaining the gage of the thread or "ball" of the rail, as in compensating for the wear thereof by suitably manipulating the wedge or cam action member 2.

15 I claim—

1. A rail fastening and gage including interacting members, one having an inclined portion, and tongues at its ends, the other interacting member having right angled end 20 portions adapted to receive said tongues, one of said right angled end portions having an inclined tongue, said inclined tongue and an end tongue of the other interacting member being adapted to engage the tie-plate and 25 the base or foot of the rail and a cam or wedge action member insertible through said interacting members and having engagement with an inclined portion of an

interacting member, said cam-action member having means adapted to exert pressure 30 upon said interacting members.

2. A rail fastening and gage including interacting members, one having an inclined portion, and tongues at its ends, the other interacting member having right angled end- 35 portions adapted to receive said tongues, one of said right angled end portions having an inclined tongue, said inclined tongue and an end tongue of the other interacting member being adapted to engage the tie-plate 40 and the base or foot of the rail, and a cam or wedge action member insertible through said interacting members and having engagement with an inclined portion of an interacting member, said cam-action member 45 having means adapted to exert pressure upon said interacting members, said tie-plate having a downwardly inclined extension adapted to engage said cam or wedge action member.

In testimony whereof I affix my signature in presence of two witnesses.

CHARLES K. McDERMOTT.
